SURGE BOOSTER DEVICE FOR EXHAUST
MANIFOLDSCharles R. Flint, La Porte, Ind., assignor to The
De Luxe Products Corporation, La Porte, Ind.,
a corporation of Indiana

Application October 21, 1944, Serial No. 559,824

2 Claims. (Cl. 60—30)

1

This invention relates to a vacuum accumulator and more particularly to a surge booster provided with a check valve and intended for application to an exhaust manifold. In my Patent No. 2,345,569, issued April 4, 1944, and Patent No. 2,390,527, issued December 11, 1945, I have disclosed check valves suitable for application to exhaust manifolds of internal combustion motors. These check valves are designed to admit air to the exhaust manifold whenever suction conditions exist therein. In the operation of the device as heretofore disclosed, it has been discovered that the effectiveness of the device has decreased under full throttle conditions as the speed of the motor increases and that above a normal operating speed of around 30-35 miles per hour the exhaust vacuum at full throttle has decreased to zero so that the device cannot operate. The present device is an improvement which, by means of an accumulator, permits intake of air to the manifold even under full throttle conditions at high speeds.

The present device also has effectively overcome a tendency of the check valve, in some cases, to be fouled by surge of gas from the exhaust. It has been found that dirt which got into the very light check valve might tend to hold it open and thereby permit more carbon or other matter from the engine to foul the valve. The present device overcomes this, and has proved effective under operating conditions so that the check valve device may be entirely free of dirt from the engine.

The device is illustrated in the drawings in which Figure 1 is a broken sectional elevation; Figure 2 is a fragmentary side elevation; Figure 3 is a sectional view of a modified form of the device; and Figure 4 is a section taken along the line 4—4 in Fig. 3.

The present system is adapted to be mounted on the exhaust manifold 10 of an internal combustion motor indicated at 11. A conventional down-draft air cleaner 12 is indicated as mounted on the intake side of the motor and supplies cleaned air thereto. The motor is preferably of the usual multi-cycle, multi-cylinder type, and a plurality of its cylinders exhaust into the exhaust manifold 10. The surge booster comprises a graduated tube 15. These graduations may be uniform and continuous, but it is more practicable to divide the tube into sections of diminishing cross-section as indicated at 16, 17 and 18. For an ordinary six to eight cylinder passenger car or light truck, an internal diameter of $\frac{1}{4}$ inch leading from the manifold for 10 or 12 inches, and connecting to

2

a tube having $\frac{1}{4}$ inch internal diameter for 10 or 12 inches, is satisfactory. In some cases it may be desirable to have a third tube 18 of $\frac{1}{8}$ inch internal diameter.

- 5 The booster tube communicates with a check valve 20 having a diaphragm 21 which is so thin as to have no substantial inertia. This check valve closes the passageway 22 which communicates with the clean air side of the filter 12.
- 10 The check valve comprises a collar 25 which is welded or otherwise affixed in the side of the air filter. A union tube 26 having an internal diameter slightly larger than that of the tube 18 connects the collar 25 with the annular valve seat 27.
- 15 The valve seat 27 has a projecting neck 28, having a face 29 against which the diaphragm 21 is pressed by the very light leaf spring 30. The diaphragm has a larger diameter than the neck 28 so that its edges project thereover into the space 31. The check valve is completed by the casing 31 which encloses the valve seat 27 and has an opening 32 communicating with the tube 18.

20 A stud 40 is secured to the casing and a packing nut 41 is screwed thereon to provide an airtight union securing the end of the tube 18.

The tension of the leaf spring 30 may be adjusted by insertion of one or more washers 33.

25 The booster tube 15 is provided, preferably near the air cleaner with a timing accumulator chamber 50 substantially larger than the tube and having a restricted orifice 51 communicating with the tube.

30 A plate of sheet metal 60, twisted into a spiral, is inserted into the lower end of the tube 16. This spiral serves the purpose of withdrawing heat from any air which enters the tube from the exhaust manifold and heating any cold air which enters it from the outside.

35 The figures in the drawing are drawn to scale, the size being of considerable importance although the spacing and size vary in accordance with the particular motor.

40 The operation of the device is as follows. When the motor is running, a series of exhaust pressure waves passes through the exhaust manifold. Each pressure wave is followed by a relative vacuum. Whenever the pressure in the manifold is greater than in the tube 15, hot exhaust gases enter the tube from the manifold and are cooled 45 by passage over the heating device 60. At the same time the sheet metal is heated. Because of the heating member 60, the gases are cooled more rapidly than would otherwise be the case. As the pressure drops in the manifold, it also 50 drops in the tube and the check valve opens, let-

ting in air from the atmosphere to the tube. The movement of air through the tube creates in its wake a vacuum which tends to keep the air moving into the tube. This is accelerated by the fact that the air is heated, particularly when it reaches the curled metal device 60.

In actual practice it has been demonstrated that the volume of air entering the exhaust manifold through the check valve 20 is considerably augmented, particularly at higher motor speeds, by the addition of the tube 15. Thus, on the ordinary motor, no air will enter through a check valve above a motor speed of 30 to 35 miles per hour at full throttle. With the present device, however, air will continue to pass in through the check valve at all normal operating speeds.

The chamber 50 serves to synchronize the timing of the booster surge or wave, the size of the orifice being of a predetermined size to bring about this synchronization. The chamber 50 serves as a timing device in that immediately following the explosion in the cylinders of the motor, the pressure within the tube 15 is raised. This compresses the air that is in the vacuum accumulator which has been drawn through the valve 20, and forces it through orifice 51 into the chamber 50. The air pressure in the chamber 50 is then considerably greater than atmospheric pressure. After each explosion, there is a delay until the vacuum comes into being and draws air through the accumulator tube 15 and valve 20. During this delay, air which is in the chamber 50 at increased pressure flows through the orifice 51 to the tube and is fed into the manifold and the motor. Thus, the chamber 50 and the orifice 51 provide a flow of air before the vacuum takes effect and eliminates any lag of air flow. The speed of air flow into and out of chamber 50 can be adjusted for any installation by regulating the size of the orifice 51. In some installations the air flow through the orifices will need to be more rapid than it will in other installations. The size of the orifice 51 may be made a predetermined size for any given engine, as shown.

In Figures 3 and 4 I have shown a modified structure and check valve.

The modified form of accumulator or booster 10 comprises a booster tube 171 adapted to be attached in any suitable way to a manifold or other structure. Ordinarily this may be by screw threading 172 of the housing 173. It will be noticed that the manifold end of the tube extends slightly beyond the end of the housing, a distance of $\frac{1}{16}$ inch being satisfactory, the tube having an internal diameter of $\frac{1}{4}$ inch. The housing 173 is shown as comprising four parts, the threaded end 175, the union 176, the chamber housing 177, and the end closure 178. It will be noted that the housing forms a housing chamber 179 about the tube 171 which chamber is not greatly larger than the tube 171. For example, with a tube $\frac{1}{4}$ inch in internal diameter the entire housing is suitably not much more than $\frac{1}{2}$ inch in diameter. The tube 171 terminates at 180 slightly short of the end 178 of the housing.

The division shown for the housing is preferred for ease of assembly. It is obvious that the entire device may be made in one piece if desired.

The union 176 is joined to the threaded end 175 of the housing in any suitable manner as by threading. The chamber housing 177 is likewise joined to the union and is preferably caused to abut a shoulder 181 therein in such manner as to permit an end 182 of the housing to extend

only slightly into chamber 183 in the neck of the check valve 110.

The preferred form of check valve is shown in my Patent No. 2,390,527. It includes a tubular neck 110. Secured to the top of the neck is a valve housing 113 which comprises a bottom housing 114, an inner housing 115, and a cover 116. A valve seat 117 is sweated within the bottom housing 114, the bottom of the seat being held in spaced relation to the bottom housing by the ring 118. The ring 118 also provides a seat for the inner cover 115. The valve seat is circular in shape and is provided with a series of valve openings 120 having substantially radial sides. The valve seat has considerable depth and the valve openings 120 are provided with a series of grooves 151 and lands 152.

The bottom housing 114, which is generally dome-shaped, is provided with an inwardly convex section 121 which limits the area beneath the valve openings. The deflector 122 consisting of a circular plate of metal having a downwardly directed edge portion 123 is mounted a predetermined distance below the valve openings and serves not only to deflect the current of air but to limit the available area in the chamber 124 formed within the bottom housing.

Between the deflector 122 and the valve openings is a thin flexible wafer spring 125. This spring is provided with a large number of peripheral fingers 126, it being preferred to have at least six of these fingers and preferably eight. The fingers are curved at their ends to press upon the valve 130. The valve is likewise a thin wafer of metal having no substantial inertia. It is in the form of an annulus, the edges 131 of which overlap slightly the valve openings. The ends of the fingers 126 touch the valve at approximately the mid-portion of each valve opening; that is, the number of valve openings is preferably the same as the number of spring fingers.

Above the valve seat is an accumulator chamber 135 bounded at the top by the inner cover 115. This chamber 135 is broken up into a series of 45 smaller chambers 136, 137 and 138 by the series of baffles 139 and 140. These baffles are of thin metal, are circular in form, and their outer edges are spaced only a very little from the wall of the inner cover 115. The lower baffle is separated 50 from the valve seat by a spacer 141 and other spacers 142 and 143 separate the second baffle and the inner housing.

The inner housing is provided with a relatively small opening 145 which communicates with the annular passageway 146 formed by the spacing of the inner cover 115 and the cover 116.

The cover is spaced from the inner cover by spacers 47; and the deflector 122 is spaced from the spring 125 by an additional spacer 148. The 60 spring is spaced from the valve seat by the spacer 149. The various spacers, the valve seat, the valve, the valve spring, the deflector, the baffles, the inner cover, and the cover are held in spaced relationship by the bolt 150. In assembling the 65 structure the various parts just referred to are assembled on the valve seat and the latter is then inserted in the bottom housing.

The figures are shown drawn to scale, and size is of considerable importance, although spacing and size are naturally varied in accordance with the amount of air which is to be passed inwardly through the structure. The dimensions given are suitable for the ordinary passenger car having a six or eight cylinder multi-cycle engine developing up to 100 horsepower.

The valve seat shown has a diameter of approximately 2 inches. The valve openings are centered at a point $\frac{5}{8}$ inch from the center of the valve seat. They are approximately $\frac{1}{2}$ inch long, along the radius, and are $\frac{3}{8}$ inch wide at their widest point and approximately $\frac{1}{4}$ inch at the narrowest point as measured between the straight sides. The valve seat is $\frac{1}{8}$ inch deep and the grooves 151 are each 0.114 inch wide and $\frac{3}{64}$ inch deep. The two lands 152 are $\frac{1}{32}$ inch wide. The bottom of the valve seat is smoothly finished.

The valve 130 is $1\frac{3}{4}$ inches in outside diameter and 0.75 inch inside diameter, and the material is between 0.003 and 0.004 inch thick, flat and free from burrs. It is preferably made from National 15 clock spring steel.

The valve spring 125 is $1\frac{3}{8}$ inches in diameter, is 0.003 inch in thickness, with the fingers depressed to give a total width of 0.075 inch. The central $\frac{3}{4}$ inch erose circle is flat and the curvature commences only at the outer edges. The fingers are approximately $\frac{1}{2}$ inch across at the outside, although the very edge is rounded.

The baffles 139 and 140 provide an annular space 0.015 inch in width between the edge of the baffles and the inside of the inner housing 115. The space between the edge of the deflector 122 and the inside of the bottom housing is approximately $\frac{1}{8}$ inch. The opening 145 in the inner housing is a circle $\frac{1}{8}$ inch in diameter.

The annular chamber 146 is approximately $\frac{3}{2}$ inch wide.

The foregoing detailed description has been given for clearness of understanding only, and no unnecessary limitations should be understood therefrom.

What I claim as new and desire to secure by Letters Patent is:

5 1. A surge booster comprising an elongated tube at least ten times as long as its diameter adapted for connection at one end to the exhaust manifold of an internal combustion engine and having an opening to the atmosphere at the other, and a check valve opening whenever pressure on the inner side of the valve is below atmospheric, said valve having a diaphragm of no substantial inertia in said opening and having heat exchange means within the tube adjacent the exhaust manifold end thereof.

15 2. A surge booster comprising an elongated tube at least ten times as long as its diameter adapted for connection at one end to the exhaust manifold of an internal combustion engine and having an opening to the atmosphere at the other, and a check valve opening whenever pressure on the inner side of the valve is below atmospheric, said valve having a diaphragm of no substantial inertia in said opening and characterized by the presence of a twisted metallic sheet having substantially the diameter of the tube within the tube at the exhaust manifold end thereof.

CHARLES R. FLINT.
